United States Patent Office.

WILLIAM BALL, OF WILMINGTON, OHIO.

Letters Patent No. 95,968, dated October 19, 1869.

IMPROVED RAILWAY MOVING-MACHINE.

The Schedule referred to in these Letters Patent and making part of the same.

To all whom it may concern:

Be it known that I, WILLIAM BALL, of Wilmington, in the county of Clinton, and State of Ohio, have invented a new and valuable Improvement in Railway Moving-Machines; and I do hereby declare that the following is a full, clear, and exact description of the construction and operation of the same, reference being had to the annexed drawings, making a part of this specification, and to the letters and figures of reference marked thereon.

Figure 1, of the drawings, is a representation of a central longitudinal section of my invention.

Figure 2 is a top view of the same.

Figure 3 is a detached view of the compound lever.

Figure 4 is a detached bottom view of the axle.

My invention relates to a means for moving cars, and other heavy bodies, running upon wheels on railway-tracks, or any smooth surface; and consists, mainly, in the construction and novel arrangement of devices whereby this object is satisfactorily attained.

The letters H H designate the timbers, forming the frame of my machine.

They are connected by the cross-beams h h.

The letters A A designate the wheels, upon which the machine moves. For railroad-work they are flanged to suit the track. They are of cast-iron, and made very stout and strong.

To the inner side of each wheel is firmly attached a ratchet-wheel, B, several inches smaller in diameter than the wheel A.

Rigidly secured to each wheel is its axle C, having two flanges, c' and c'', and a spindle-end, a, which is inserted into one end of the coupling D.

E designates a movable ring, having a groove in its bore, to fit on a corresponding longitudinal rib formed on the axle, whereby it is prevented from revolving on the axle.

F designates a forked lever, pivoted to the metal bar k, at f, and working in a groove circumscribing the ring E, whereby the teeth of the ring and coupling D are made to interlock, when it is desired to work both wheels together as if they had a common axle. Thus the wheels may be worked independently or not, as desired.

The forked lever F and ring E may also be used as a brake, by forcing the outer rim of the ring against the collar c' of the axle.

G is the bearing-plate of the coupling D.

L L, the journal-plates of the axles, fitting between the flanges c' and c'', and braced by the central struts n n, of the braces N N.

P P are the moving-levers, each of which is forked

at the fulcrum p, and terminates in the hinged hooks p' and p'', which work respectively, above and below, in the teeth of the ratchet-wheel B. When it is desired to use the lower hook p'', so as to give a pushing movement, the upper hook is thrown back from the ratchet-wheel.

The connecting-bar s, of the levers r r, is released from the pin t, thus allowing the coiled spring g to hold the hook p'' against the ratchet-wheel.

In order to give a pulling movement, the upper hook p' is thrown forward on the ratchet-wheel, with which it engages, by its weight, and the lower hook p'' is held back from the teeth of the ratchet-wheel by means of the levers r r and pin t, easily adjusted.

In order to connect this machine with a car, or other heavy body, the double lever M M' is used.

M is the long operating-lever, having its fulcrum, m, secured to the central timber H, at its junction with the cross-beam h.

V is a ratchet-bar, serving to hold the lever M in any desired position.

M' is the biting-lever, pivoted to the lever M, and forked, terminating in the two teeth i i, between which and the upper surfaces of the beams H H the platform of a car, or other accessible part of any heavy body, is seized, and held securely.

The forked lever M' works in the two fulcra m' m', secured to the beams H H, near their ends.

It is apparent that the wheels A A will always be pressed firmly against the track, and, therefore, but little liable to slip, as the weight and moving-power are applied at opposite ends of the machine.

In furtherance of this object, the levers P are so arranged that the power is always applied to them by bearing down.

What I claim as my invention, and desire to secure by Letters Patent, is—

1. In combination with the wheel A, the compound lever P, spring g, and ratchet-wheel B, substantially as set forth.

2. The moving-machine, herein described, having ratchet-wheels B B, compound levers P P, forked double lever M M', braces N N, coupling D, forked levers F F, and toothed rings E, constructed and arranged to operate substantially as specified.

In testimony that I claim the above, I have hereunto subscribed my name, in the presence of two witnesses.

WILLIAM BALL.
